United States Patent Office.

ANDREW J. FLETCHER, OF RED BLUFF, CALIFORNIA.

Letters Patent No. 101,722, dated April 12, 1870.

IMPROVEMENT IN HAIR MEDICINE.

The Schedule referred to in these Letters Patent and making part of the same.

To all whom it may concern:

Be it known that I, ANDREW J. FLETCHER, of Red Bluff, Tehama county, State of California, have invented a certain "Improved Medical Compound" for the improvement and restoration of the hair and for the cure of all diseases of the scalp, and of which the following is a full and exact description.

To enable others skilled to make and use my invention, I will proceed to describe its component parts.

I take of sweet oil of almonds, 2 ounces; aqua ammonia, 2 ounces; spirits of rosemary, 8 ounces; distilled water, 4 ounces; extract of manzanita, 1 ounce; or, if this cannot be obtained readily, I substitute some quassia chips, about half an ounce, to be well soaked in distilled water, and the extract to be put in with the compound.

I mix the above ingredients well together, and apply them to the head in the usual form of a lotion. After it is well rubbed on, the head should be brushed with a soft hair-brush.

This compound will prove an infallible remedy where the hair is coming out through sickness or any other cause, and will restore hair where the applicant is bald; it also cures tetter and other diseases of the scalp.

I am aware that some of these ingredients have been before used for the purposes named, but from experiments made, and from a long residence on the Pacific coast and in Mexico, I have found that these ingredients, when combined with the manzanita extract—a shrub indigenous to Mexico and the Pacific coast has a most wonderful and curative effect. When, however, this cannot be obtained, I use a few chips or gratings of the quassia tree, which I find, in combination with the other ingredients, produces the same beneficial results.

Having thus fully described the nature of my improved medical compound, and the method of applying the same,

What I claim as new, and as my invention, and desire to secure by Letters Patent, is—

The medical compound as described, for the uses and purposes set forth.

A. J. FLETCHER.
